Douglas*Assistant Examiner*—R. Spear*Attorney, Agent, or Firm*—Kilgannon & Steidl**[57]****CLAIM**

The ornamental design for a pinch operated dispensing actuator cap, as shown and described.

DESCRIPTION

FIG. 1 is a perspective view of a pinch operated actuator showing my new design;

FIG. 2 is a top plan view thereof;

FIG. 3 is a front plan view thereof;

FIG. 4 is a side plan view thereof;

FIG. 5 is a rear plan view thereof; and,

FIG. 6 is a bottom perspective view thereof, wherein the internal configuration of the actuator, shown in phantom, is not part of the design.

The phantom lines in FIG. 6 are for illustrative purposes only and form no part of the claimed design.
